(57) **CLAIM**

I claim the ornamental design for a motor scooter, as shown
and described.

DESCRIPTION

FIG. 1 is a front view of a motor scooter showing our new
design;

FIG. 2 is a rear view thereof;

FIG. 3 is a top view thereof;

[FIG. 4] 4 is a bottom view thereof;

FIG. [5] 5 is a right side view thereof;

FIG. [6] 6 is a [diagonally forward right side] *front and right
side* perspective view thereof;

FIG. [7] 7 is a [diagonally backward right side] *rear and right
side* perspective view thereof;

FIG. [8] 8 is a [diagonally forward left side] *front and left side*
perspective view thereof; and,

FIG. [9] 9 is a [diagonally backward left side] *rear and left
side* perspective view thereof.

1 Claim, 9 Drawing Sheets

**Matter enclosed in heavy brackets [ ] appears in the
original patent but forms no part of this reissue; matter
printed in italics indicates the additions made by reissue.**
